COMBINED TOP GUARD RAIL AND CONTROL PANEL FOR A COOKING RANGE OR THE LIKE

Frank Breckenridge, Whittier, and Thomas D. Tweedie,
Monrovia, Calif., assignors to O'Keefe & Merritt Company,
Los Angeles, Calif., a corporation of California

Application April 8, 1958, Serial No. 50,382

Term of patent 14 years

(Cl. D81—25)

Fig. 1.

Fig. 2.

Fig. 1 is a front perspective view of a combined top guard rail and control panel for a cooking range, or the like, embodying our new design; and,

Fig. 2 is a fragmentary cross-sectional view on the line 2—2 of Fig. 1 in the direction of the arrows.

The dominant features of the design reside in the portions shown in full lines.

We claim:

The ornamental design for a combined top guard rail and control panel for a cooking range or the like, as shown and described.
